UNITED STATES PATENT OFFICE.

JOSEPH C. LUSSE AND ROBERT J. LUSSE, OF PHILADELPHIA, PENNSYLVANIA.

DESIGN FOR AN AMUSEMENT CAR.

Application filed August 6, 1927. Serial No. 23,017. Term of patent 14 years.

To all whom it may concern:

Be it known that we, JOSEPH C. LUSSE and ROBERT J. LUSSE, citizens of the United States, residing in Philadelphia, Philadelphia County, Pennsylvania, have invented a new, original, and ornamental Design for an Amusement Car, of which the following is a specification, reference being had to the accompanying drawing forming part thereof, in which the single figure of the drawing is a perspective view of an amusement car embodying our new design.

We claim:

The ornamental design for an amusement car substantially as shown.

JOSEPH C. LUSSE.
ROBERT J. LUSSE.
